UNITED STATES PATENT OFFICE.

HENRY F. SCHLUETER, OF CINCINNATI, OHIO.

SEWING-MACHINE.

SPECIFICATION forming part of Letters Patent No. 243,729, dated July 5, 1881.

Application filed November 18, 1880. (No model.)

To all whom it may concern:

Be it known that I, HENRY F. SCHLUETER, of Cincinnati, in the county of Hamilton and State of Ohio, have invented a certain new 5 and useful Improvement in Sewing-Machines; and I do hereby declare the following to be a full, clear, and exact description of the same, reference being had to the accompanying drawings, forming part of this specification, in 10 which—

Figure 1 is a side elevation of the mechanism for operating the feed-shaft or shuttle-arm of a sewing-machine, part of the latter being shown in section. Fig. 2 is a rear-end view 15 of the same, also showing part of the machine in section. Fig. 3 is a plan view of the forked end of the shuttle-arm, and Fig. 4 is a perspective view of the guide-block for the connecting-rod.

20 Similar letters of reference in the several figures denote the same parts.

My invention relates to that class of sewing-machines wherein the feed-shaft is driven from the main shaft by a connecting-rod and eccentrics and the shuttle-arm is oscillated in some 25 manner by the movements of the connecting-rod; and it has for its object to simplify and improve the means by which the shuttle-arm is operated.

30 To this end the invention consists, mainly, in the combination of a bell-crank lever and a vibratory link with the connecting-rod joining the main and feed shafts, the lever being pivoted at its angle to the frame of the machine 35 and jointed at its lower end to the rear end of the shuttle-arm, and the link being pivoted at one end to the short arm of the lever and at its opposite end to the connecting-rod, the operation being such that the connecting-rod 40 transmits its motion to the shuttle-arm to reciprocate the shuttle through the medium of the link.

In the accompanying drawings, A represents a part of the frame of a sewing-machine. 45 B is the main or driving shaft, having its bearings in the upper part of the frame. C is the feed-shaft, having its bearings in the lower part of the frame; and D is the connecting-rod, connecting these two shafts by eccentrics or wrists,

for the purpose of driving the feed-shaft from 50 the main shaft B. The center of the connecting-rod is slotted or made with a large opening, E, to receive a square guiding block V, F, fitted upon a cross-rod, G, in the upright of the frame, so as to turn freely on such rod when 55 the connecting-rod is operated. The block F serves to guide and steady the connecting-rod in its movements, and is formed with a flange on one side to prevent it from slipping too far through the slot in the connecting-rod, while 60 a pin, h, is inserted in the cross-rod G, outside of the block, to prevent it from slipping out of the slot in the connecting-rod. One side, I, of the opening in the connecting-rod is made movable by screws or other means for access 65 to the block when occasion requires it, and its ends are beveled to fit against corresponding seats on the rod, for the purpose of adjusting such side I to compensate for the wear of the block.

J is the bell-crank lever, of unequal length, and hung upon the cross-rod G within the frame A. The long lower arm of the lever is formed with a ball to fit within the forked rear end of the shuttle-arm K, which is pivoted at 75 L under the table of the machine, as shown in the drawings. The forked end of the shuttle-arm is slotted back of the fork, and a screw, m, passes through the forks for the purpose of adjusting their bearings upon the ball of the 80 lever.

N is the link by which the short arm of the lever is joined to the connecting-rod, just below the upper eccentric, and by which the motion of the rod is transmitted to the lever. 85 When the machine is in operation the upper pivoted end of the link rises and falls with the connecting-rod, thereby oscillating the bell-crank lever on the cross-rod G and causing its lower end to vibrate to operate the shuttle-arm, as will be fully understood. The connection between the lever and link may be varied or made adjustable to regulate the throw of the shuttle-arm by any suitable means. The connections between the shuttle-arm and connecting-rod being few in number and reduced to small bearing-surfaces, the friction of the parts is much decreased, thereby causing the 90 95

mechanism to run smoothly, and are of such character as to prevent them from easily working loose.

The ways formed by the block F and slotted connecting-rod guide and steady the latter in its movements without undue lateral strain, and for this reason work easily and smoothly.

Having thus described my invention, what I claim as new is—

10 The combination of the rod D, connecting the main and feed shafts, and slotted to re-

ceive the pivoted guide-block F, with the link N, bell-crank lever J, and the shuttle-lever and feed-shaft, substantially as described, for the purpose specified.

The foregoing specification of my invention signed by me this 23d day of October, A. D. 1880.

HENRY F. SCHLUETER.
